TELEPHONE-EXCHANGE SYSTEM.

1,416,088.

Specification of Letters Patent. Patented May 16, 1922.

Application filed March 14, 1905. Serial No. 250,055.

To all whom it may concern:

Be it known that I, EDWARD E. CLEMENT, a citizen of the United States, residing at Washington, in the District of Columbia, 5 have invented a certain new and useful Improvement in Telephone-Exchange Systems, of which the following is a specification, reference being had therein to the accompanying drawing.

10 My invention relates to telephone exchange systems, being applicable also to telegraph and other systems of analogous nature. It has for its object the provision of means for the interconnection of subscribers' or other lines with apparatus and 15 circuits composed in part of what are known as "manual" devices, and in part of what are known as "automatic" devices; or in other words the object is to combine the best 20 known features of manual and automatic apparatus and methods so as to eliminate the defects of each and retain the benefits of both, obtaining in addition considerable economies both in installation and in operation 25 as a direct result of the combination.

The present application is in part a division of my former application filed September 19, 1904, Serial No. 225,058, for telephone systems and apparatus and method of 30 operating the same. The invention herein set forth is in the nature of an improvement on the systems patented to me April 3, 1900, by Letters Patent, 646,675 and 646,677.

The present system embodies the best features of modern common battery manual exchange systems, and also the best features at present known, of the standard automatic exchange apparatus known as the "Strowger". In addition, I have embodied a considerable number of new features, and have solved a considerable number of problems in effecting the combination desired.

In my improved system I divide the work to be done into three parts, giving the first 45 part to the subscriber, the second part to an operator, and the third part to a machine. At the subscriber's station I provide any suitable or well known type of common battery telephone, with two-line binding-posts and two extra posts, one of which is a ground post. With the telephone, and connected to these binding-posts, I provide a compact make and break signal apparatus capable

of sending four numbers or more, using both sides of the line and ground in order to facilitate transmission. I employ impulse transmitters which have been described in my own patents above referred to, in Patent 757,030, granted April 12, 1904, to E. A. Faller, and others. I shall therefore not describe all the mechanical details of the impulse transmitter I employ, this forming no direct part of the present invention, except in combination with other features. From a subscriber's station a pair of line-wires 55 pass to the central office, being there normally connected through the contacts of a cut-off relay with a standard form of line-signal-controlling-magnet and battery. The subscriber's ringer may be either in a ground tap with a condenser, or it may be bridged when the hook is down. On party-lines the ringers may be either connected from opposite sides to ground, or they may be bridged,—in either case with or without condensers.

The central office end of each line is normally disconnected from the outside part of the line at the cut-off relay, but is connected permanently to an answering-jack on the 80 manual switch-board, with which is associated the line-signal referred to and also to multiple terminals in the banks of the automatic switches. In addition to these terminals, each line may have further multiple-jacks or terminals, on other manual switchboards, to increase the flexibility of the system.

Cooperating with the answering-jacks on the manual or answering switch-board sections, I locate pairs of plugs, with connecting cords, and I bridge the main battery across each pair of cord conductors between the windings of a pair of signal-receiving relays. From each manual switchboard 95 trunk-lines lead to automatic connectors, these being in groups and each group containing the multiple terminals of subscribers' lines. On the switchboards these trunk-lines terminate in jacks and the trunks are multiplied to all the switchboard sections so that all the trunks in the exchange 100 can be reached by any operator. Each trunk-jack has associated with it a "busy" signal such as a lamp, and whenever a 105 connection is made through one of the

trunks by plugging into its jack at any switchboard section, its busy signals are at once lighted over its multiple jacks at all the sections. Each trunk line at the switch 5 end has a pair of bridged magnets with battery between them. These magnets are controlled over the cord-circuit and trunk from the calling subscriber's station (or from a repeater in the operator's cord-circuit) and the magnets in turn control the automatic switch to select the line wanted, one relay controlling the vertical magnet of the switch, the other controlling the rotary magnet of the switch, and both together 10 jointly controlling the release magnet, the test and other mechanism.

The operation of the system in brief is as follows:—A calling subscriber sets his number-wheels to form a desired number and 20 takes down his receiver. This closes the line-signal relay at central and lights the line-lamp. The operator at the switchboard, perceiving this signal, inserts an answering-plug in the answering-jack, thus bringing 25 the bridged relays of the corresponding cord-circuit into connection with the line, and also bridging the main battery at the same time. The cut-off relay of the line may be bridged across the connective terminal, but 30 is preferably connected to an extra contact in the line-jack and to extra bank contacts in the multiple switches to be described. Hence, when connection is made with the line either through the jack or through a 35 connector switch, a local circuit is closed through the cut-off relay to energize the same, whereupon it cuts off the line from the line relay and battery, and puts it onto the jack and multiple terminals.

40 Thereupon the subscriber's apparatus gets current through the cord, the signal-wheels are tripped by a suitable detent-magnet put in circuit when they are set, and the first signal numbers come into central, affecting 45 the bridging relays in the cord, which set a number-signal showing preferably the first two digits of the line-number wanted, corresponding of course to the group-number of the connector-trunk. In other words, suppose 50 the subscriber has set up the number 4468. When the operator plugs in, her cord indicator turns at once to 44 and she therefore puts the second plug into a jack of number 44-group. Thereupon the subscriber's 55 number-wheels send the last two digits over the cord and over the trunk to affect the bridged relays of the switch, this being thereby stepped up and around to the desired contact, which is then tested to ascertain 60 if it is busy. The test is accomplished in this way: When the switch is down or in normal position it mechanically closes a circuit-closer which is then held by a magnetically controlled latch. This circuit-closer 65 when closed breaks both sides of the trunk-

circuit between the controlling relays and the switch, cuts off the ringing relay (or both ringing relays if selective apparatus is employed), cuts off the release-magnet from the trunk-relays, bridges a test magnet 70 across the wiper-terminals of the switch and puts the release-magnet under control of the test-magnet. At the same time it gives control of its own tripping-magnet to the trunk-relays jointly. 75

Now suppose the wiper to have come on the desired terminals. If the line is idle there will be no bridged battery on it at the central office end, hence the test relay of the switch will get no current, and the switch 80 will therefore remain in contact with that line. In ringing (as will be hereafter stated) one of the trunk-relays is up and the other back, or at this juncture both may be back; this closes the circuit of the trip-magnet 85 which unlatches the above-mentioned circuit-closer with the following results: the test relay is cut off, the continuity of the trunk is restored subject to the ringing relays, the trip-magnet is cut off and the release-magnet of the switch is put back under control of the trunk-relays. Ringing then 90 proceeds as I will trace later.

If on the other hand the line wanted is busy, the test-relay will get current as soon 95 as the wiper-terminals come on that line contact (the trunk relays being suitably energized at the same time) the release-magnet is then energized, the switch is returned to normal position, and buzzer or other suitable current is sent back to the calling subscriber's station to indicate to him that the line wanted is busy. He then hangs up his receiver, giving a clearing-out signal to the switch-board operator, who pulls the plugs, 100 whereupon all parts are again in their normal condition of disuse.

My invention is illustrated in the accompanying drawings, in which Figure 1 is a diagram of a subscriber's sub-station apparatus; Figure 2 is a similar diagram made to appear as an extension of Figure 1, and showing the exchange end of the subscriber's line, and an operator's cord-circuit; Figure 3 is a similar extension diagram showing the 110 trunk extending from the operator's position to an automatic switch. Figure 3^a is a plan view of the contact bank of the switch in Figure 3. Figure 4 is a face view of a switchboard employing my invention; and Fig. 5 is a plan view of a portion of the operator's key shelf thereof.

Referring to Figure 1, I have shown the line-wires 1 and 2 passing from the central office to the subscriber's station A. This 125 comprises the usual transmitter T, receiver T', switch-hook H, ringer Q and a signal transmitting device comprising a series of wheels with cooperating contacts, controlling magnets and a push-button for ringing. 130

This signalling apparatus is preferably housed in a small casing separate from the telephone, with which it is connected by the wires 3, 4 and 5, a ground wire being added which is common to both the ringer and the signal box. I do not fully illustrate the latter, and except for its cooperation with the other parts it directly forms no portion of the present invention. When unset, the signal box has the circuits of all its wheels open, and maintains the talking circuit 1—2—3 closed at the contacts w^{13} — w^{14} , which are normally maintained closed by a cam w^{18} on the wheel shaft w^{20} . There are four wheels w , w' , w^2 and w^3 , giving the necessary four digits to transmit numbers up to 9999; but it is possible to increase the number of wheels for a larger number of exchange lines. I have indicated these as mounted in pairs on the two shafts w^{19} and w^{20} , each driven by its own spring and each fitted with a terminal cam w^{17} or w^{18} . Each shaft is geared to a train and is restrained when set by a magnet W or W', the former in a ground wire 8 and the latter in a similar ground wire 9 from their respective shafts or wheels, to a common ground. Each wheel has peripheral teeth, the two wheels of each pair preferably having their teeth staggered with relation to each other. The cam on the end of the shaft w^{19} closes together the contacts w^{16} and w^{12} when its train is run down, so as to cut in the succeeding train and magnet. The four wheels are separately movable to set them so as to form any desired number, as will be readily understood by those skilled in the art. As I have shown them they are in pairs, the first pair held when set by a detent on the armature of magnet W, whose circuit is closed when they are set. These two wheels transmit thousands and hundreds, or the number of a trunk group, as will appear later. The other two wheels, w^2 — w^3 , transmit tens and units, or the number of a line in the automatic switch banks. This pair is held when set by a detent on the armature of magnet W'. Both magnets hold their trains until released from central, the second magnet W' requiring a make and a break to do this, the detents on its armature constituting a two-step escapement.

At the central office the line wires 1 and 2 are connected to the springs m^4 and m^{10} , respectively, of the cut-off relay M. These two springs are normally in contact with the springs m^8 and m^{14} , connected respectively by wires 13 and 12 to the line relay L^a and battery, and by the wire 21 to a balancing coil L' and battery. The relay L controls contacts in the local circuit 11—12—26—27—28—ground, containing the line signal lamp L'. When the relay M is energized the relay L is cut off, and the line momentarily broken, after which the springs m^4 and m^{10}

are in contact with the springs m^8 and m^{14} , connected respectively by wires 14 and 22 and extensions 15—16 to the jack springs J'—J², also by extensions 29—30 to the multiple terminals J³—J⁴, etc., in automatic switch banks. It will be observed that the spring-jack J and the multiple terminals are therefore disconnected from the line when the latter is in a condition of disuse. They can only be cut on when the relay M is energized. When energized it disconnects the line 1—2 from the signal relay and battery and connects it to the jack and to the multiple terminals.

Referring now to Figures 2 and 3, which represent the exchange end of a line, and the circuits and apparatus of an operator's cord, with the terminals of a trunk line, P and P' are the operator's plugs, or at least one pair of them, connected by the cord conductors 33—35, 34—36. Each side of the cord circuit is separated by the condenser C or C' into two parts, connected through the condensers inductively. The purpose of this separation is to give control of the lines from the condensers back to the calling subscriber direct, and from the condenser forward to the same subscriber indirectly during calling and to the called subscriber directly after connection is made. This will appear more fully later. The cord relays V and R respond to impulses from the subscriber's station and repeat these impulses to the trunk lines on the opposite of the condensers.

Relay V is connected from the cord conductor 33 by wires 37—38—39 to the battery bus-bar 11 connected to main battery B. By reference to Figures 2 and 3 it will be observed that I have shown the trunks supplied from one battery and the incoming lines and the cord circuits from another. This gives one battery for calling subscribers as such and the other for called subscribers as such, which in many cases is desirable. Moreover, where the calling subscriber is located in one exchange and the called subscriber is located in another it is imperative not to depend upon one source of energy to supply both ends of the long line. In the present case I provide for this contingency perfectly, while leaving the continuity of the through line for telephonic currents undisturbed.

Relay R is connected by wires 40—41 from the cord-conductor 34 to the battery bus 10. Bridged across the bus-wires 10 and 11, the main battery B is grounded at its middle point so as to give two batteries of equal or approximately equal potential for the two sides of line using a ground return. The arrangement described bridges the relays V and R across the calling end of the cord, 33—34, with the battery B, and also gives each relay a path to ground through

one side of the battery. The relay V, I shall call for convenience the vertical relay, and the relay R, I shall call the rotary relay, designating the two sides of line 1-33-57, 5 and 2-34-58, in the same way. This is because the relay V ultimately controls the vertical magnet of the automatic switch, while the relay R controls its rotary magnet. Both these relay together control other 10 things. The armature v controls the springs v' , v^2 , v^3 , v^4 , v^5 , v^6 , all of which are normally open except the last, which is closed on wire 43 to the corresponding spring v^5 of relay R. The latter relay 15 through its armature r similarly controls the springs r' , r^2 , r^3 , r^4 , r^5 , r^6 , all of which are normally open except the last.

In addition to the vertical and rotary relays, I provide a pilot relay N, which 20 operates with the other relays in the control of the various pieces of apparatus. The plug P' has three contacts, p , p' , p^2 . The last two form the terminals of the main talking conductors 33, 34, 35, 36, but the 25 sleeve p is connected to an independent or third conductor 61. This sleeve cooperates with sleeve J^{15} of the trunk-jacks to close local circuits.

Associated with each cord-circuit and pair 30 of plugs is an indicator F-F', comprising two magnets in separate local circuits 64 and 65, for convenience provided with a common ground return 66. The wire 65 passes to the spring N' of the pilot relay N, and thence to the spring 35 N' of the pilot relay N, and thence to the spring v' of the vertical relay V. When the latter is energized the spring v^2 is closed against v' , and battery current is supplied through the wire 42 by the path traced to 40 the magnet F'. The wire 64 from magnet F passes to the spring N' of relay N, thence by spring N' to spring r^2 of rotary relay R, and when the latter is energized to the battery wire 42, the relay R thus controlling 45 magnet F, while the relay V controls the magnet F'. Obviously these connections may be reversed so that each relay will control the other magnet. The magnet F controls a pawl f^5 which meshes with a ratchet 50 wheel f^7 connected to the wheel f which carries numbers. Similarly the magnet F' controls a pawl f^6 meshing with a ratchet wheel f^8 connected with a number-wheel f' . A common retaining pawl (not shown) meshes 55 with both ratchets and remains in mesh until both armatures are released and remain back for a definite length of time. Thus each magnet may step around its wheel separately, and both wheels will be retained 60 in the positions to which they are set until the magnet circuits are broken, when a spring or other means f^4 on the shaft f^3 , and the connecting shaft f^2 , will restore the same to zero. Indicators of this general character 65 are well known in the art, and detailed de-

scription or illustration is therefore unnecessary, particularly as my own type of indicator which I use forms no essential part of the present invention. Any equivalent indicator may be substituted in this system, its function being to show the operator the thousands and hundreds digits, or the trunk number, of the switch trunk which is wanted. 70

Associated with the cord-circuit is a clearing out lamp L². This lamp is jointly controlled by the vertical and rotary relays and the pilot relay N. In order that the lamp may light, both relays V and R must be de-energized, and the pilot relay must be energized. The latter condition only occurs when the plug P' is in a trunk jack, the circuit 75 61 being then continued through the sleeve p of the plug to the thimble J^{15} of the trunk jack, by wire 69 to the relay L² of the busy trunk lamps L³ and L³⁰, and by wire 68 to the battery. It will be understood that while I have shown grounds for the return current from these various pieces of apparatus, this is for convenience of illustration only. All battery connections may be solid wires if desired or necessary. 80 90

Immediately upon the insertion of the plug P' the relays N and L² get current and pull up their armatures, and the lamps L³ and L³⁰ light to show that the trunk is busy to operators at other sections. Here again I may reverse the connections and have the lamps normally lighted when the trunks are idle, putting them out for busy trunks, by 95 relays or otherwise. The arrangement I show is preferable however.

When the pilot relay N is energized by the insertion of the plug P' in a trunk jack, it cuts off the indicator F-F', and momentarily breaks the battery connection through wires 38 and 39 to the cord conductor 33, at the contacts N⁸-N¹⁰, immediately making it again at the contacts N⁸-N¹⁰. The purpose of this is to let the second half of the subscriber's signal come in. 100 110

In addition to the above features I provide a busy back signal connection and relay for each cord. For this I use a special generator G, of any preferred type giving 115 current which will create a characteristic sound in the calling subscriber's receiver to apprise him that the wanted line is busy, and the frequency of change in this current should be such with relation to the constants 120 of the relays V and R, and V'-R' (Fig. 3) that it will not leak back on the main battery wires. The bus-wires 57-58 are connected through contacts e^6 and e^7 to wires 53-54 and so to the cord conductors 33-34. 125

This current is put on by the busy relay E, whose armature e^2 when attracted closes the contact e^3 , which closes the circuit of the magnet e^4 . This magnet e^4 is connected to wire 33 by the wire 53 when its armature e^7 130

is attracted. This relay e^4 is in parallel with the relay V, one terminal of each being connected to the bus-bar 11 of battery B. This relay will continue to hold up its armatures 5 so long as the calling subscriber has his telephone removed from the hook. Across the armatures e^6 and e^7 a generator or interrupting machine is connected by the wires 57' and 58'. The contact e^8 is connected by the 10 wire 54 to the wire 34. This bridges current from the generator across the strands 33 and 34 and the current will in turn be transmitted through the line wires 1 and 2 to the subscriber's telephone. This busy 15 signal will continue until the subscriber hangs up his telephone and de-energizes the magnet e^4 whose armatures e^6 and e^7 will fall back and disconnect the generator current.

20 The magnet E which controls the busy back, is sluggish in its action, and has two differential windings e and e' put on the core end to end, so that for battery current passing through the windings serially the 25 magnet is neutral; for battery current passing through the windings in parallel, that is in the same direction, the magnet is active; but for voice currents the windings are impossible, and neither winding by itself will 30 pull up the armature. These two windings are connected in a bridge across the conductors 35-36, which may be traced as follows: 35, 47, e' , 46, v^3 , v^4 , 44, 45, r^4 , r^2 , 49, e , 48, 36. This is grounded at its middle point between 35 the contacts v^4 and r^4 of the relays V and R. In the normal forward transmission of signals the impulses caused by either relay do 40 not affect the magnet E, which serves then merely as an impedance to prevent the shunting of voice currents, if any. After the connection is completed the magnet remains bridged until clearing out, but if the line wanted is busy current comes back over 45 both sides of the trunk 57-58 in parallel, the magnet E is energized, and the busy back signal is given.

The generator G may be common to the entire exchange.

Passing now to Figure 3, I have therein 50 shown the circuits, and indicated the apparatus of an automatic switch connected to the trunk line 57-58. I provide one or more of these switches for each divisional group of subscribers, preferably for each 55 hundreds group. The actual number I usually provide is 5% of the total number of subscribers, or five switches for each one hundred subscribers, to each of which every subscriber's line in that hundred is multipled. The five multiple terminals $j^a-j^a-j^b$, etc., of line 1-2 in Figure 2 are supposed to 60 appear in the banks of the five switches assigned to the hundred group in which the line belongs. If the number of this line be 65 for instance 4468, its multiples will appear

in the banks of five switches all numbered 44. From these five switches five trunk lines are led to the manual switchboard shown in Figure 4 and are there connected to the trunk jacks J' in each of the separate positions, so 70 that before each operator on the switchboard there are five jacks constituting a group numbered 44, by plugging into any one of which she can reach a switch, or rather the subscriber can be put on a switch having line 75 terminals of lines all numbered in 4400. The subscriber has then only to select the tens and units of the particular line wanted by the automatic switch, and he has his connection. 80

Returning to Figure 3, the main principle of control is simply that of bridging two magnets with the main battery across the metallic circuit, and controlling the magnets separately for some purposes and jointly for others. The magnets V' and R' are bridged across the trunk circuit 57-58, with the main battery B² by a path traceable as follows: 57-74-V'-95-y'-y-77, battery b-b'-79-R'-78-58. It will be observed 90 that the connection of V' with the conductor 95 is by way of contacts controlled by the relay Y, this being the test relay. When this relay is energized the magnet V' is taken off the wire 77 leading to the battery bus-wire 95 10², and is put on the other battery wires 113, 11², thus placing the portion b' of the battery B² to both sides of line through both relays V' and R'. This is for sending the 100 busy back signal that I have mentioned in connection with relay E in Figure 2, the current so sent energizing that relay to put the generator G on the calling line. The sending back of current in this way is only 105 momentary so far as the test relay Y is concerned, but the generator C stays on the line until the subscriber hangs up.

The relay V' controls a magnet V², through the springs v^8 , v^{10} , closed together to put battery on the magnet when the relay 110 is energized. Relay R' controls magnet R² in the same way through springs r^7 , r^9 . These two magnets are the vertical and rotary magnets of the switch, respectively. They have a common return wire 83 which 115 passes through normally closed contacts on the pilot or latch switch X, and to magnet wires 82 and 82', whereby they are cut off after the desired connection is obtained. Here, as in the cord circuit of Figure 2, the 120 local controlling magnets for the signal are of no use after their function is performed and a pilot switch of some kind is the proper thing to cut them off and leave the line relays V' and R' or V and R thereafter to 125 control the testing, ringing and clearing out. It is by this successive manipulation of the local circuits that I am enabled to employ the same bridged relays V, V', R, R', for 130 so many different purposes. The pilot switch

X is an aggregation of contact springs with platinum contact points, as all the switches and relay contacts are supposed to be herein, in accordance with the best practice at this time. The several sets of springs are connected mechanically to be operated together through the agency of a bar of insulation x, which carries the ends of the long springs x², x⁵, x⁸, x¹¹ and x¹³. When down this switch makes the following connections and disconnections: 1st, the wires 72—73 leading to the wiper contacts s and s' are disconnected from the wires 70—71 of the trunk, and are connected to the wires 91 and 89 leading to the test relay Y through contacts k²—k³ on relay K, so that the relay K must be de-energized if the test relay is to act. 2d, the vertical and rotary magnets V² and R² have their circuits completed through springs x¹⁴—x¹³—x¹⁵. 3d, the release magnet Z is disconnected from its normal terminals v¹⁰ and v¹⁰ of relays V' and R', and connected to battery wire 177 on one side and to spring y² of test relay Y on the other. 4th, the latch magnet X' of the pilot switch itself is given control of all these connections because the switch is held down by a latch engaged by the armature of the magnet X' and released when the latter is sufficiently energized. I say sufficiently energized because this magnet is sluggish, for a purpose which will appear in the statement of operation.

The pilot switch X is forced down to the latched position shown in Figure 3, by any suitable part of the mechanical switch mechanism in its return to normal after connection. In the figure I have indicated this as an arm on the main spindle of the switch, which strikes the bar x in descending and forces the springs down into the position shown, where they are held by the latch controlled by magnet X'.

When magnet X' is energized to release the switch X, the following connections and disconnections are made: 1st, wires 72 and 73 are disconnected from the test relay and are continued to wires 70 and 71, by way of the contacts k⁵, k⁶, k⁸ and k⁹ of relay K, this being a ringing relay which breaks the line back when ringing forward. 2d, the vertical and rotary magnets V² and R² have their circuits broken at contacts x¹²—x¹³—x¹⁵. 3rd, the release magnet Z again connected to the contacts v¹⁰ and v¹⁰ of relays V' and R', being disconnected from the contacts of the test relay. 4th, the latch magnet is left idle without further control of the pilot switch, which remains up with the last connections intact until the end of the connection and the return of the main switch to normal or zero position.

The ringing relay K is controlled by the relay V' in the following way: Relay K is connected on one side to a back contact v⁹ of relay V', and on the other side to the wiper S³. In order to energize relay K it is necessary that relay V' be energized and the relay R' be de-energized simultaneously, and the wiper S³ resting on the contact leading to the line cut-off relay M. It will be seen that cut-off relay M is energized through the winding of the ringing relay K, the energizing circuit being from battery B², through 79', r⁷, r⁸, 80', v⁷, v⁹, K, 89', s³, 75 J¹¹, 30, M, 12, 10, B and ground. This relay is cut off after ringing, and to provide for means to continue to energize the relay M a resistance coil B is connected to the wiper S³ in multiple with the relay K. This resistance coil, as will be seen, is connected permanently to both the wiper and battery and so cannot be cut off in any way. The calling subscriber rings in the following way: The wheel w³, in the transmitting device, is provided with a long make contact which grounds the line 1 over which the relay V' is controlled. This ground is of long enough duration to hold up the armature of relay V' until the ringing relay K can connect 90 generator current across the called line. While this long contact is made by the number-wheel w³, the opposite side of the line No. 2 is broken by the number-wheel w². This in turn de-energizes the relay R' which 95 is necessary to operate the ringing relay K. The subscriber is provided with a push-button P for ringing again, if necessary. This button P grounds No. 1 side of line and opens No. 2 side of line just the same at the 100 number-wheels w² and w³, and the calling subscriber can ring as many times as he desires.

Before proceeding to the statement of operation I shall refer to some additional matters which are of importance in the system but which have been omitted from the illustration for the sake of simplicity. Referring to Figure 2, it will be recalled that I described the trunk jacks as being arranged 110 in groups, those of each group connected to automatic switches containing multiple terminals of the same lines. I have also described the number of such group, when one of its switches is wanted, as being designated to the operator by the indicator F—F'.

In Figure 2 I have shown a pair of plugs P²—P³ united by cord conductors 300—350, 340—360, intended to cooperate with the jack terminals of the subscribers' lines to 120 connect the same at will with other subscribers or with trunk lines leading to the chief operator, to a special manual operator, to long distance, or the like. In order to call for this service a subscriber according to 125 my system need not set his impulse transmitter at all, but simply works his hook up and down, which by opening and closing his line circuit rapidly, causes his line lamp L' to flash. Upon perceiving a flashing lamp, 130

the operator inserts a plug P^2 , and puts the twin plug P^3 into a jack J^2 of the office line 200, which puts the subscriber on a manual switchboard, where his call will be answered 5 by an operator with whom he can converse and who can give him connection, receive his complaints and the like, the same as in any manual system now existing. If a subscriber's transmitting apparatus is out of 10 order, or for any reason he fails to obtain a desired connection, he can always get an operator to whom he can complain, and who can give him an emergency connection. For this purpose I provide the manual operators 15 in the exchange, including the long distance and toll-board operators, etc., with a set of trunks leading to automatic switches uniform with the others and containing subscribers' multiple-terminals.

20 The operation of my system thus described is as follows: Suppose subscriber A desires to call another subscriber whom I will designate as 8753. Subscriber A first sets his four number-wheels w , w' , w^2 and w^3 , 25 and takes down his receiver. He gets no current as yet in the latter, the talking circuit being open after he sets his wheels. The wheels w^2 — w^3 are cut out, with their magnets, at the springs w^{16} — w^{12} , and as the 30 magnet W' requires a make and a break to release its wheels the latter remain set. The magnet W on the other hand gets current as soon as its wheels are set, by the following circuit: main battery b' , 10—21, balancing 35 coil L^a , m^{14} , m^{10} , 2, 11, w^{20} , w^{21} , (the armature being mechanically advanced into attracted position by the finger w^{17a} on the shaft) W , 8, 10 x , ground, and back to battery. This current energizes magnet W , 40 holds the wheels set. The subscriber then taking down his telephone energizes the line-relay L and lights lamp L' . The cord-conductors are then connected through the jack of the respective line wires, and at the 45 same time the extra contacts on the jack close the third wire local circuit to the cut off relay M , which pulls up its armature m^4 and m^{10} . The magnets L^a and L are thus cut off, and the wires 1—2 are continued 50 through springs m^6 and m^{12} to the jack springs j' , j^2 .

In connecting the line through to the jack, it was momentarily broken at springs m^{10} , m^{14} , hence current was cut off from magnet 55 W , which may control its own circuit so as to stay cut off, or whose armature may be mechanically trapped in any well known manner so that it will not again engage the wheel after releasing it. The two wheels w and w' now start to revolve, and each makes and breaks its own side of line a number of times corresponding to its setting, in this case 8 and 7, respectively. These impulses go in alternately, because although the line 60 might be closed at intervals without damage,

I do not care to have both sides open at once until the signal is set and noted, although even this would be no drawback if the magnets F and F' be made sluggish as regards the full retraction of their armatures. The 70 impulses coming in over the vertical and rotary sides of line affect the relays V and R to set the signals F — F' to 87. This action is almost instantaneous, and the operator noting the number, takes up the companion plug P' and inserts it in a trunk jack of the group bearing that number in some one of the panels T^o before her or her right or left hand neighbor in the same section. The insertion of this plug closes the following 80 circuit locally: battery b' (Figure 3), 68, L^x , 69, J^{15} , p (Figure 2), 61, N , 62 and through ground back to battery. The relay N then pulls up, disconnects the signal magnets F — F' , and momentarily breaks the circuit 85 through wires 38—39 which is the holding circuit of the substation magnet W' and which was initially closed when the first two wheels w and w' ran down. The momentary break in the holding circuit of the magnet 90 W' allows the right hand armature of said magnet to be retracted and release the wheels w^2 — w^3 and as the plug P' is then in the trunk jack, these wheels now send their impulses on over the trunk. In the present 95 case I have included condensers C in the cord circuit, in order to separate the battery feed, and inasmuch as the relays V — R respond to all impulses anyhow, I employ them for repeating by causing them to 100 ground the two sides of the cord conductors 35—36 as they work. In the branch from each side is included one winding of the relay E .

Referring now to Figure 3, as the number 105 53 comes over the two wires the relay V' gets five impulses, and the relay R' gets three. These alternately make and break the local circuits of the vertical and rotary magnets V^2 — R^2 , whereby the switch terminals s — s' 110 are set upon the contact of the line wanted. Ordinarily, that is when it is any other line than his own, the calling subscriber's wheels then leave the circuit open or closed for a brief time, during which the relay Y remains 115 bridged by itself across the wanted line terminals. This time is long enough to permit the relay to be effectively energized if the line is busy and has battery bridged across it, the relay being sufficiently sluggish so 120 that it will not respond to purely momentarily impulses as the wipers s and s' pass over the contacts of lines not wanted, to reach the contacts of the line wanted. If that line is idle, these terminals are disconnected as shown in Figure 1, and therefore the relay Y gets no current. The last number-wheel in running down places a passing ground on line wire No. 1. This occurs as 125 the last impulse comes in. The same thing 130

is accomplished by the subscriber pushing the button. The immediate effect of this is to pass current through the relay V which grounds the conductor 35 causing current to 5 pass through relay V' which attracts its armature and the circuit of the ringing relay K is then completed. This relay pulls up its armature connecting the generator G' to the springs k⁵, k⁸ and also closes the circuit of the latch magnet X', which pulls up 10 its armature and releases the pilot switch X. This rises, cuts off the vertical and rotary magnets V², R², connects the wire 73 from the wiper terminal s' to the spring k⁸ and 15 generator. It also connects the wire 72 from the wiper terminal s to the spring k⁵ and generator, disconnects the test relay and puts the release magnet under the joint control of the relays V' and R'. It will be observed 20 that as soon as the pilot switch X has operated the wires 70 and 72, 71 and 73 are continuous, hence battery current will pass forward over the called subscriber's line, the cut-off relay M being energized disconnecting 25 the line-signal apparatus and connecting the line straight through. Now suppose the line wanted was busy when the connection was first effected, the grounding of one side of the line by the subscriber and the working 30 of the relay K, whereby the latch magnet is actuated has not yet occurred. The test relay is energized, and separates its contacts y y' and closes together its contacts y' y² and y⁸, when bridged across a busy 35 line. Such a line will be supplied with current through the windings of relays V and R if it is a calling line or through the windings of the relays V' and R' if it is a called line. The relay magnet V' is thus taken off 40 of battery wire 77 and is put on the battery wire 113, the same side as the relay magnet R'. Current then flows from the side b' of battery through these magnets in parallel back through the trunk line wires in parallel, 45 through the branches 47-46 and 48-49 in parallel and through the closed contacts r³, r⁴ and r², r⁴ in parallel and to ground, passing the windings e, e', also in parallel and energizing the relay E. This attracts its 50 armatures, closes the contact e² and e³ which in turn closes the circuit of the busy back generator, which remains closed until the calling subscriber hangs up.

At the same time the test relay Y closes 55 the circuit of the release magnet Z which restores the switch to its normal position and clears the trunk. The relay V' is then put back on its proper side of battery for the next call.

60 The structure of the switch of Figure 3 needs no detail description, as it involves the usual vertical and rotary ratchets for the spindle S, cooperating with pawls controlled by the vertical magnet V² and the 65 rotary magnet R², which in turn are con-

trolled by the vertical and rotary relays V' and R' respectively. In order that the wipers may have free movement over the contacts, they engage the ends thereof instead of the sides as in some other forms of switch. 70 This is diagrammatically shown in Figure 3 and it should be remarked that the wipers while shown as of flat spring metal may of course be varied as to their form and arrangement, the only requirement being that 75 they shall preserve their alignment with respect to the spindle, and at the same time maintain pressure of their tips against the inner ends of their bank contacts. Subject to this change in the method of effecting 80 contact, standard types of switch may be employed. This simultaneously operating two-way switch is shown in my former application Serial No. 225,058, of which the present application is in part a division. 85

Having described my invention, what I claim is:

1. In a telephone exchange system, subscribers' lines having terminal line signals at the central office, a centralized source of 90 current supply therefor also at the central office, and means at the subscribers' stations to determine the flow of current therefrom in the lines, automatic switching apparatus at the central office adapted to effect connection with the lines, means controlled by an operator for connecting a calling line with the automatic switching apparatus, magnetic controlling means for said switching apparatus and connections therefrom to said 95 centralized source, together with means at the subscriber's station for controlling current flow from said source through said magnetic controlling means for the purpose of setting said switching apparatus to select a wanted line, means in said switching apparatus for testing the selected line to ascertain if it be already engaged, and means dependent upon the result of said test for maintaining talking circuit continuity between the calling and the wanted subscribers' lines, substantially as described. 100

2. Connecting means for telephone systems consisting of answering terminals and a series of switching or connecting terminals, a certain number of subscribers' lines being connected with their answering terminals in one group, and a certain number of lines being connected to the switching or connecting terminals in one group, of trunk 115 lines leading from each group of answering terminals to the various groups of switching terminals, automatic switching apparatus connected with each trunk-line and adapted to co-operate with one group of 120 switching or connecting terminals, together with means under the control of an operator to connect an answering terminal in her group with a trunk leading to any desired switching apparatus and group of connect- 125 130

ing terminals, and further means whereby said switching apparatus may be controlled over the trunk by the calling subscriber, substantially as described.

5. 3. Connecting means for telephone systems consisting of answering terminals and a series of switching or connecting terminals, a certain number of subscribers' lines being connected with their answering terminals in one group, and a certain number of lines being connected to the switching or connecting terminals in one group, of trunk lines leading from each group of answering terminals to the various groups of switching terminals, automatic switching apparatus connected with each trunk-line and adapted to co-operate with one group of switching or connecting terminals, together with means under the control of an operator to connect an answering terminal in her group with a trunk leading to any desired switching apparatus and group of connecting terminals, a source of current common to a plurality of the lines and trunks and supplying them with energy both for talking and signaling, and further means whereby current from said source may be controlled through the trunks by the calling subscriber for the operation of the automatic switch, substantially as described. 75

30 4. In a telephone-exchange system, a switchboard, subscribers' lines provided with terminals upon said switchboard, a number signal registering device and an automatic connecting means adapted to be successively placed, by an operator, under control of a subscriber in response to a signal, substantially as described. 80

40 5. In a telephone system, a central office, subscribers' lines radiating therefrom, each provided, at the subscriber's station, with a normally-open selective transmitting-circuit, and a normally-closed signal-receiving circuit, and at the central office with a normally-closed calling signal-circuit; means whereby the subscriber may close his selective signal-circuit, and thereby operate the central-office signal, cord circuits for inter-connecting the lines, cord circuit signals and 45 automatic connecting devices at the central office adapted to be operatively connected to the subscriber's line while disconnecting the central-office calling signal therefrom, and clearing out means for the automatic devices adapted to be controlled by the subscribers, substantially as described. 90

50 6. In a telephone system, a subscriber's line, provided at the subscriber's station, with telephonic apparatus normally disconnected therefrom, a signal receiving device normally connected thereto, an impulse transmitter and a magnet controlling the same, in a circuit normally broken at said transmitter, a signal for the line at the central office, a magnet for controlling the same, 95

and a battery, both normally connected to the line, the battery current being of a proper character to operate the signal-magnet, and also the transmitter-magnet at the subscriber's station, when said transmitter is set, operator's connective means at the central office, adapted to be connected to the line wires while disconnecting the signal-magnet therefrom, a responsive circuit-controlling device in circuit with said connective means, and suitable connections whereby the condition of current in the line is changed in the act of making connection therewith so that the subscriber's transmitter-magnet is operated, and the circuit-controlling device affected in response thereto, substantially as described. 100

7. In a telephone exchange system a switchboard divided into sections, subscribers' lines connected to terminals grouped thereon, trunk lines, answering and connecting plugs at each station, each answering plug adapted to be connected to any one of a set of trunks upon different panels, automatic means connected with the trunk circuits and adapted to be controlled by the subscribers for effecting final connections, and a number signal device for each answering plug connected to its circuit, and a suitable generator, substantially as described. 105

35 8. In a telephone exchange system, a series of line and multiple terminals and a series of automatic directly driven connector switches, said multiple terminals being distributed among the banks of the respective switches, the terminals of each line being normally disconnected therefrom, and a cut-off relay for each line controlled in making connection therewith to connect it with said terminals, substantially as described. 110

45 9. In a telephone exchange system, subscribers' lines, answering terminals for manual connection with the lines, automatic switches, connecting terminals distributed in the banks of automatic switches and normally disconnected from the lines, and means controlled through said connecting terminals to connect their line thereto. 115

50 10. In a telephone exchange system, subscribers' lines, line terminals therefor at a central office normally disconnected from their respective lines and connected to signal devices, automatic switches co-operating with said line terminals, means whereby a calling subscriber may control a switch for effecting a connection between his line and another, and means operated through said line terminals and co-operating contacts, of a wanted line to connect it to its said terminals, substantially as described. 120

55 11. In a telephone exchange system, subscribers' lines, automatic connector switches having terminals corresponding to said lines but normally disconnected therefrom, means whereby each switch may be connected tem- 125

porarily to a calling subscriber's line, means in each switch circuit to test the wanted line to ascertain if its terminals are connected or not, that is if it is busy or not, 5 and a relay for each line to connect all its terminals so as to test busy when connection is effected with any of them, substantially as described.

12. In a telephone exchange system, subscribers' lines, answering terminals and multiple connecting terminals therefor, a common source of current supply, automatic switches less in number than the number of lines for making connection with the 15 multiple terminals, a line-signal for each line and a cut-off relay adapted to be energized by current automatically supplied from said source through a switch when connection is made with the line to disable the 20 signal, substantially as described.

13. In a telephone exchange system, subscribers' lines, answering terminals and multiple connecting terminals for each line, the former disposed in answering groups 25 with line-signals, and automatic switches having banks containing the latter, a relay for each line normally disconnecting the multiple terminals therefrom but adapted when connection is made with the line to 30 connect the terminals thereto, and means for actuating the automatic switches adapted to be controlled by calling subscribers, substantially as described.

14. In a telephone exchange system, subscribers' lines, answering terminals and multiple connecting terminals for each line, the former disposed in answering groups with line signals and automatic switches having banks containing the latter, a relay for each 40 line normally disconnecting the multiple terminals therefrom but adapted when connection is made with the line to connect the terminals thereto, and means for actuating the automatic switches adapted to be controlled by calling subscribers, through their 45 answering terminals, substantially as described.

15. The combination with a telephone line having a limb extending to the central office, 50 of a plurality of terminals therefor each having a contact adapted to form a portion of the line circuit and normally insulated from line and from ground, an automatic switch and its circuit having testing apparatus co-operating with said terminals, a relay 55 to connect said normally insulated contacts with the limb of the line when actuated, means to change the electrical condition of said contacts when so connected, a controlling 60 magnet and a battery associated with said switch circuit, and a switch at the subscriber's station, whereby when a connection is made, said contacts are charged for the 65 purposes of testing, said terminals are placed in operative relation with the line

and said controlling magnet is placed under the control of the subscriber's apparatus, substantially as described.

16. The combination with a telephone line 70 of a test-terminal normally disconnected therefrom, a relay for connecting said test terminal with the line, an automatic directively controlled selector switch with testing apparatus, a circuit terminating in said switch, controlling apparatus associated with the switch circuit, a source of electricity 75 also associated with the switch circuit, and means for closing the circuit of said source over the telephone line to operate the said controlling apparatus, and a 80 circuit also through said relay, when connection is made with the line, substantially as described.

17. In a telephone exchange system, the combination with subscribers' lines having 85 answering jacks and multiple terminals, of operators' cord circuits and automatic switches each containing the multiple terminals of a certain number of subscribers' lines, and means at each subscriber's station 90 for actuating and restoring said switches, together with trunk lines leading directly from the several operators' positions to the automatic switches, whereby a calling line may be trunked by an operator 95 to the automatic switch containing a terminal of the line wanted, substantially as described.

18. In a telephone exchange system, subscribers' lines, trunk lines terminating in 100 automatic switches and associated through the switches each with the same determinate group of subscribers' lines, said switches containing each multiplied terminals of the same group of lines, means operable by an operator in response to a call to connect the calling line at one point to any of said switch-trunks, and controlling means for the switch then operable by the subscriber 105 to select and connect with the line of the wanted subscriber at a separate point, substantially as described.

19. In a telephone exchange system, subscribers' lines having answering terminals and multiple terminals, said answering terminals being grouped upon a manual switchboard before operators, and automatic switches with said multiple terminals grouped in their banks, trunk lines leading directly from said automatic switches to 115 said switchboard, and means controlled by the operators at said switchboard to connect any calling line with any of said trunks and thence to its automatic switch, together with means controlled over the subscribers' 120 lines for restoring said automatic switches, substantially as described.

20. In a telephone exchange system, subscribers' lines, a manual switchboard having one or more answering panels fitted 130

- with answering terminals for said lines, automatic switches containing multiple terminals for the several lines, trunk lines leading directly from said switches to the 5 manual switchboard and there terminating in one or more trunk-panels, together with means controlled by an operator to connect a calling subscriber to an idle trunk, and actuating means for the trunk switch controlled thereafter from the subscriber's station, substantially as described. 70
- 10 21. In a telephone exchange system, subscribers' lines and automatic switches, line terminals for said lines for answering purposes located upon a manual switchboard and multiple terminals for connecting purposes under the control of the automatic switches, said switches being arranged in groups, those in each group containing multiple terminals for the same group of subscribers, and all the switches of each group being connected directly by trunk-lines to multiple connecting terminals upon the manual switchboard, together with means 15 under the control of an operator to connect a calling line with the trunk of an idle switch in any desired group, and actuating means for said switch controlled thereafter from the calling subscriber's station, substantially as described. 75
- 20 22. In a telephone exchange system, subscribers' lines and automatic switches, line terminals for said lines for answering purposes located upon a manual switchboard and multiple terminals for connecting purposes under the control of the automatic switches, said switches being arranged in groups, those in each group containing multiple terminals for the same subscribers, and 25 all the switches of each group connected by trunk-lines to multiple connecting terminals upon the manual switchboard, together with means under the control of an operator to connect a calling line with the 30 trunk of an idle switch in any desired group, and a busy signal circuit associated with each multiple-trunk terminal on the switchboard so arranged that when a trunk is in use, that trunk will test or signal busy to 35 all operators until the end of the connection, when it is again idle, substantially as described. 80
- 40 23. In a telephone exchange system, subscribers' lines, answering-terminals therefor upon a manual switchboard, trunk-lines with automatic switches at one end, and at the other end connective terminals on said switchboard, a busy signal associated with each trunk-terminal on the switchboard, and 45 means for displaying all the busy signals corresponding to a particular trunk when connection is made with any terminal thereof, substantially as described. 85
- 50 24. In a telephone exchange system, subscribers' lines and line terminals therefor, 55 a series of automatic switches and trunk-lines connected thereto, with multiple line terminals in the switches and connective-terminals for the trunks, together with operators' cord-circuits for connecting a calling line with any desired trunk-line giving direct access to a particular switch and thereby to its group of subscribers' multiple terminals, and subscribers' sending and switching devices for switch control thereafter, substantially as described. 90
- 60 25. In a telephone exchange system, a subscriber's line-circuit, a cord and plug adapted to be connected therewith when calling, an automatic switch containing multiple terminals of subscribers' lines and a trunk-line for the switch terminating in a jack adapted to cooperate with said plug, together with number indicating means at the central station whereby the calling subscriber may inform the operator of the trunk connection desired, and means at the subscriber's station for controlling the trunk switch thereafter, substantially as described. 95
- 65 26. In a telephone exchange system, a subscriber's line and a terminal cord and plug adapted to become connected thereto in calling, a plurality of automatic switches each containing multiple terminals of a plurality of subscribers' lines, a trunk line leading to 70 each switch, each trunk line terminating in a jack, means at the central office for designating the particular trunk line required, and means at the subscriber's station for actuating the same and thereafter for actuating the automatic switch connected with that trunk to select the subscriber wanted, substantially as described. 100
- 75 27. In a telephone exchange system, a subscriber's station provided with a talking set and a signal transmitter, a line circuit therefrom to a central office, an operator's cord circuit adapted to be connected with the line at the central office in response to a call, a plurality of trunk lines and automatic switches associated therewith, each switch arranged to make connection between its trunk line and a plurality of subscribers' lines, an indicating device associated with the operator's cord circuit and controlling 105 magnets for each switch, whereby a calling subscriber may first designate to an operator the trunk connection desired, and thereafter may control the automatic switch associated with that trunk to continue the connection ultimately to the line wanted, substantially as described. 110
- 80 28. In a telephone exchange system, line terminals at a central office normally disconnected from battery, with means to connect battery thereto in making connection with the line, an automatic switch provided with controlling magnets and a test magnet, the former being normally connected so as 115 to respond to current over a calling sub- 120
- 85 90 95 100 105 110 115 120 125 130

scriber's line in making a selection, and the latter normally connected to the switching terminals to be brought into circuit with the terminals of the wanted subscriber's line, together with a release magnet controlled by the test magnet during selection, and thereafter controlled by the calling subscriber, substantially as described.

29. In a telephone exchange system, a two wire subscriber's line, and two wire connecting circuits, an automatic switch adapted to be controlled by a calling subscriber to make connection with the line of a wanted subscriber, controlling magnets for said switch normally energized over the line-circuit and controlled by the calling subscriber, a test-magnet normally connected to the switch terminals so as to be brought in circuit with the wanted subscriber's line for test, a release magnet primarily controlled by the test-magnet, and means actuated in completing a connection to disconnect said test-magnet and to place the controlling-magnets under the joint control of the connected subscribers, substantially as described.

30. In a telephone exchange system, controlling magnets, a metallic talking circuit normally severed and having one end connected to said controlling magnets which are adapted to be controlled from a calling station, and having the other end normally connected to a test-magnet for testing the condition of the line wanted, with means to disconnect said test-magnet and restore the continuity of the talking circuit in completing a connection, and ringing means bridged across said metallic circuit, substantially as described.

31. In an automatic switch, controlling magnets adapted to be controlled from a calling station, a metallic talking circuit normally severed and having one end connected thereto, and having the other end normally connected to a test-magnet for testing the condition of the line wanted, with means to disconnect said test-magnet and restore the continuity of the talking circuit in completing a connection, and further means becoming operative upon the restoration of the switch to a condition of disuse to again sever the talking circuit therethrough and to connect the test magnet as before, together with ringing means bridged across said metallic circuit, substantially as described.

32. In an automatic switch, controlling magnets adapted to be controlled from a calling station, a metallic talking circuit normally severed and having one end connected thereto, and having the other end normally connected to a test-magnet for testing the condition of the line wanted, with means to disconnect said test-magnet and restore the continuity of the talking-circuit in completing a connection, and further means actuated by the switch in returning to its nor-

mal condition of disuse to again sever the talking circuit and connect the test-magnet as before, together with ringing means bridged across said metallic circuit, substantially as described.

70

33. An automatic exchange switch provided with a plurality of subscribers' line terminals and a pair of selective terminals co-operating therewith, a metallic talking circuit through the switch connected to said selective terminals and adapted to be extended back to a calling subscriber, a source of current bridged across said metallic circuit and a pair of controlling magnets for the switch included in said bridge with the battery, an intermediate ground connection for the battery, and means at a calling subscriber's station for controlling the flow of current in either side of the metallic circuit separately and independently of the other, whereby each controlling magnet may be separately energized, together with a ringing generator, a ringing relay controlled by one of said magnets and itself determining the connection of the ringing generator to the circuit, substantially as described.

34. An automatic exchange switch provided with a plurality of subscribers' line terminals and a pair of selective terminals co-operating therewith, a metallic talking circuit through the switch connected to said selective terminals and adapted to be extended back to a calling subscriber, a source of current bridged across said metallic circuit and a pair of controlling magnets for the switch included in said bridge with the battery, and intermediate ground connection for the battery and means at a calling subscriber's station for controlling the flow of current in either side of the metallic circuit separately and independently of the other, whereby each controlling magnet may be separately energized, together with a ringing generator, a ringing relay controlled by said magnets to determine the connection of the ringing generator to the circuit, substantially as described.

35. In a telephone exchange system, subscribers' metallic circuits, metallic circuit automatic switches, and metallic connecting-circuits, together with a bridged common battery having intermediate ground connection and serving a plurality of the subscribers' lines, and controlling magnets for the several switches connected to the metallic circuits in series with the parts of said battery, together with means at the subscribers' stations to determine the joint and separate action of said magnets, substantially as described.

36. In a telephone exchange system, a switch having a pair of wiper contacts relatively movable with regard to subscribers' line terminals, a talking circuit extending from said wiper contacts, a pair of con-

- trolling magnets for producing the adjustment of said wiper contacts to any desired subscriber's line terminals, connections back from the switch to a calling subscriber, a 5 busy signal normally inoperative with respect to said subscriber, a test relay for the main switch, and a pilot-switch normally connecting the same to the wiper contacts to test a wanted line, means controlled by said 10 test-relay to connect the busy signal to the calling line if the line wanted is busy, and means to actuate the pilot switch to disconnect the test-relay and complete the circuit for conversation when the line wanted is 15 idle, substantially as described.
37. In a telephone exchange system, subscribers' lines and automatic switches for interconnecting the same, operators' plug-circuits for connecting the lines to the switches, 20 and signal repeaters associated with said plug-circuits, together with a signal register operated thereby, substantially as described.
38. In a telephone exchange system, subscribers' lines and automatic switches, operators' circuits for connecting the lines to the switches, indicating means associated with the operators' circuits and controlled by calling subscribers to designate the switch connection wanted, together with means controlled by an operator in continuing a switch connection to disable the indicator, substantially as described.
39. In a telephone exchange system, subscribers' lines, connective circuits and automatic switches associated therewith, a common source of current supply for said lines and switches, means manually controlled by an operator to directly connect and disconnect a calling line with and from an automatic switch, controlling magnets for the switches, signals associated with the manual connecting means, and means whereby said controlling magnets and signals may be actuated by the subscriber whereby the 45 switches will be automatically cleared out and indications given to the operator for taking down the manual connecting means, substantially as described.
40. In a telephone exchange system, subscribers' lines, an operator's cord-circuit, connective trunks for said lines arranged in groups, automatic visual means connected with the cord-circuit for indicating the trunk leading to the desired line and an automatic 50 switch for effecting connection between the trunk and the desired line.
41. In a telephone exchange system, subscribers' lines, an operator's cord-circuit, connective trunks for said lines arranged in groups, automatic visual means connected with the cord-circuit for indicating the trunk leading to the desired line and an automatic 55 switch for effecting connection between the trunk and the desired line, said switch being 60 under the control of the calling subscriber.
42. In a telephone exchange system, subscribers' lines provided with a series of signal wheels, an operator's cord-circuit, connective trunks for said lines, means actuated by the operation of certain of said signal 70 wheels for automatically indicating to the operator the trunk leading to the desired line, means actuated by other of said wheels for automatically effecting connection of the trunk line with the desired line.
43. A telephone system comprising a "connector", a manual switchboard provided with an operator's connecting-cord, a suitable connection between the "connector" and the manual switchboard, and a busy-release- 80 circuit for insuring an automatic release of the "connector" under certain conditions, said automatic release-circuit including a talking strand of the said connecting-cord.
44. A telephone system comprising a "connector" having vertical and rotary motion provided with a plurality of line-terminals, each terminal comprising a plurality of contacts, and a plurality of relays, a contact of each line-terminal being permanently 85 grounded through one of said relays.
45. A telephone system comprising a subscriber's line, a relay for said line, a "connector", and two energizing circuits for said relay, both of said circuits being controlled by said "connector".
46. A telephone system comprising a subscriber's line, a relay individual to said line, a "connector", an operator's plug-switch, and three energizing-circuits for said relay, two 100 of said circuits being controlled by the "connector", and the third circuit being controlled by the plug-switch.
47. A telephone system comprising a "connector" provided with release mechanism, and having talking-conductors, and a busy-release-circuit for preventing the "connector" from interfering with a busy connection, said circuit including a talking-conductor of the "connector".
48. A telephone system comprising an electrically-propelled and step-by-step-actuated switching machine provided with a plurality of line terminals, means for establishing a guarding potential at any terminal 105 of a line which is busy, and a busy-release circuit including a talking conductor when the machine attempts to establish connection with a line-terminal having guarding potential, whereby the machine is prevented from 115 establishing connection with a busy line-terminal.
49. In a telephone exchange system, the combination of a subscriber's telephone line, a spring jack for said line, an automatic 120 connector having a terminal of said line, a cord and plug adapted for insertion in said jack for extending a calling connection from said line, means for controlling said connector to establish a connection with said 125 130

line, common battery means for supplying current to the line for talking purposes, said spring jack and connector terminal being connected in multiple.

5 50. In a telephone exchange system, the combination of a subscriber's telephone line, a spring jack for said line, an automatic switch provided with voice-current conductors, a cord and plug adapted for insertion in said jack for extending a calling connection from said line, means for controlling said switch to establish a connection with said line, and common battery means for supplying current through said voice-current conductors to said line for talking purposes.

51. In a telephone exchange system, the combination of a subscriber's telephone line, a spring jack for said line, an automatic switch provided with voice-current conductors, a cord and plug adapted for inser-

tion in said jack for extending a calling connection from said line, means for controlling said switch to establish a connection with said line, common battery means for supplying current through said voice-current conductors to said line for talking purposes, and a common battery circuit including contacts of said jack and plug. 25

52. In a telephone system, a plurality of 30 subscriber's lines divided into groups, means including an automatic connector switch having one motion to select groups and a second motion to find a called line in a selected group, and a busy test circuit including a portion of the talking circuit. 35

In testimony whereof I have affixed my signature in presence of two witnesses.

EDWARD E. CLEMENT.
